FRANCIS J. VITTM, OF NEWBURYPORT, MASSACHUSETTS, AS-SIGNOR TO WILLIAM N. ELY.

Letters Patent No. 84,025, dated November 10, 1868.

IMPROVED HAND-PEGGING MACHINE.

The Schedule referred to in these Letters Patent and making part of the same.

Be it known that I, FRANCIS J. VITTM, of Newburyport, in the State of Massachusetts, have invented certain Improvements in Hand-Pegging Machines, of which the following is a full and exact description.

The object of my invention is to so construct a hand-pegging machine, and to so adapt it to a crank-shaft, that, while the machine is held to the work, as it passes over it, with one hand, the movements of the awl and peg-driver, and of the feeding-devices, are actuated or managed with the other; or, while the shoe is stationary, the machine shall be carried over it, and its several parts be actuated by means of a crank and handle.

Prior to my invention and adaptation of the crank, operated by the hand, twenty years' skill and invention, (from 1834, or thereabouts,) had been expended upon hand-peggers, in which the blow given to the awl and peg-driver was imparted by means of a hammer, held in one hand, while the machine was held with the other. After the blow, the bars were elevated by means of springs.

No successful machine was ever constructed in this manner, to my knowledge. For some reason, either from the effect of the kind of blow upon the bars, or from the inequality of the blows given, the machines, by breakages or otherwise, were essentially inoperative.

I conceived the idea of so constructing, adapting, and arranging the parts as to elevate the bars, by means of a crank-handle and cam, or ratchet-bar and section of pinion, and to depress them by means of a spring, thus securing greater ease of operation, and greater uniformity of blow. Many supposed that, the machine being held by the hand upon the work, this mode would be inoperative, as it would require the machine to be held rigidly in its place to resist the reaction of the spring, but I found the invention to be a practical success.

So far as the drawings in this application are concerned, my improvements are applied to a hand-pegging machine, invented by E. M. Stevens, and patented, August 6, 1861.

This machine is in some respects more simple than any other. The awl operates as a feeding-instrument, and his devices for supplying the peg-wood are better than any I had previously contemplated. My improvements, however, can, with equal ease, be applied to any other hand-pegger.

In the drawings, A is the frame; B is a head or stock, to the under side of which are affixed the peg-driver bar and the awl-bar. The peg-driver bar b is a prolongation of the head B, or it is rigidly attached to it; or it may be pivoted to it. The awl-bar C is pivoted to the head B at c, so as to swing from and towards the driver.

D is a flat spring, fastened to the driver-bar, at d, and pressing against the awl-bar. Above the head rises a spindle or rod, surrounded with a spiral spring,

I, its top pressing against the frame, and its bottom against the head.

In Figure 1, upon the head B, is a pin, F, against which acts a cam, E, upon a shaft, e, and having a crank-handle, a a'. An awl is to be inserted in the lower end of the awl-bar, and a peg-driver in the lower end of the driver-bar.

The machine being placed with the bars down, as represented by black lines, (the awl in the leather,) and the crank being turned downwards and upwards, the cam E, in rising, acts upon the pin F, and raises the bars to the position represented in red lines. The spring I is compressed, and, as the cam turns and releases itself from the pin F, the pin falls off, and the spring drives down the bars, the awl making a hole, and the driver driving a peg.

In the lower part of the awl-bar is a small notch, n, into which falls the lower end of a cam-shaped dog, G, pivoted to the frame at g, and having a small shoulder, H, on its upper and outer end, striking against a pin, h, in the frame, to prevent its turning up and over too far. When the awl descends, the lower point of the dog engages in the notch n in the awl-bar, and, as the bar ascends, the dog turns, and the awl-bar is crowded back, or, rather, with the awl in the leather, the machine is moved forward on the work the distance of a peg-hole.

The forward edge of the awl-bar, fig. 1, is made with such a slant that, on coming down, it will so operate on the dog as to engage it in the notch without the use of a spring.

It is evident that both the awl and driver-bars may be rigidly attached to the head, and rise and fall perpendicularly, or they may be so constructed as to rise and fall alternately perpendicularly, in which case the machine is to be fed forward by some other means.

A centring or feeding-point may be used in advance of the awl, or between the awl and peg-driver, which may be operated by the awl-bar, or piston and spring, or by means of a cam. In my earlier experiments, I used a swinging point in advance of the awl, up to which I moved my machine.

Instead of the cam and pin, I have used a geared rack and cam, or part pinion, as in Figure 2, the rack R appearing on the head, and the pinion r so arranged that its teeth shall, on the revolution of the crank, take into the teeth of the rack and elevate the bars. As the crank is turned, and the teeth cease to act, the bars fall off, and are driven down by the spring. This may be found preferable on some machines.

What I claim, and desire to secure by Letters Patent, is—

1. A hand-pegging machine, so constructed, arranged, and adapted as to its several parts, that, while the machine is held to the work, as it passes over it, with one hand, the movements of the awl and peg-driver, and of

the feeding-devices, shall be actuated or managed with or by means of the other, substantially as described.

2. So constructing, arranging, and adapting the parts of a hand-pegging machine, as to operate the same by means of a crank, turned by the hand of the operator, substantially as described.

3. Arranging and adapting a crank-handle, cam, and spring in a hand-pegging machine, in combination with the awl and peg-driver bars, or either of them, substantially as and for the purposes described.

4. Arranging and adapting a crank-handle and cam, in a hand-pegging machine, in combination with an awl or piercing or pointed instrument, as a feeding-device, substantially as described.

5. The ratchet-bar and pinion, in combination with

the awl or peg-driver bar in a hand-pegging machine, substantially as and for the purposes described.

6. Constructing the bar C in connection with the dog G, so that the latter may operate without the aid of a spring, substantially as described.

7. The combination of the portable frame with crank-handle, cam, spring, and piston, all constructed to operate substantially as described.

In testimony whereof, I have hereunto subscribed my name.

F. J. VITTM.
